UNITED STATES PATENT OFFICE.

ROSCOE V. JEFFERSON, OF CHICAGO, ILLINOIS.

FLUID-FUEL BURNER.

Original application filed October 25, 1922, Serial No. 596,783. Divided and this application filed November 5, 1923. Serial No. 672,705.

To all whom it may concern:

Be it known that I, ROSCOE V. JEFFERSON, a citizen of the United States, and a resident of the city of Chicago, county of Cook, and State of Illinois, have invented certain new and useful Improvements in Fluid-Fuel Burners, of which the following is a specification.

My invention relates to a fluid fuel burner, and has for its object to provide such a new and improved burner with means for fully distributing the fuel and for supplying an ample amount of air to said fuel and to properly distribute and atomize said fuel with said air to insure complete combustion thereof.

Other objects will appear hereinafter.

This application is a division of my application for fluid fuel burner and supply apparatus, Serial No. 596,783, filed October 25, 1922.

The invention consists in the combinations and arrangements of parts hereinafter described and claimed.

The invention will be best understood by reference to the accompanying drawings forming a part of this specification, and in which,

Fig. 1 is a plan view of my improved burner; and

Fig. 2 is a vertical sectional view taken on line 2—2 of Fig. 1.

In the drawing, I have shown my improved burner mounted on a fire grate 8 of a furnace, on which the burner may be readily mounted. This burner is of the gravity supply type, and comprises an air distributing member 9 in the form of a vertical cylinder provided at its lower end with an integral catch pan 10 and a seat 11 for reception of an air pipe or air conduit 12 which extends to a suitable opening on the furnace, such as an ash door (not shown), or a suitable opening may be provided in the furnace wall, and any suitable draft control may be provided in said air conduit. A top plate or heating plate 13, provided with a central cut out or dished portion 14 and a beveled edge 15, is removably mounted, as by means of threads, on said member 9, and a fuel supply pipe or

feed pipe 16 is threaded on said top plate 13, communicating with the dished portion 14 and extending through member 9 and through the air conduit 12 to a suitable fuel supply. A curved plate or cap 17 is mounted over said top plate 13 by means of short legs 18 seated in said dished portion 14, or said cap may be mounted on said top plate in any suitable manner so as to provide an annular space 19 of the proper depth between said cap and plate to suit the particular liquid or gas used with said burner. The outer edge 20 of said cap 17 is bent down to direct the fuel downward onto a series or set of annular ring-like members or baffle plates 21, 22 and 23, which have upturned peripheral flanges 21', 22' and 23', respectively, to retain a small quantity of fuel; and said plates are of increased diameter in downward succession, the lower one being of slightly smaller diameter than the catch pan 10. A plurality of series of restricted air openings 25 are provided around member 9, being arranged above each baffle plate, and additional air openings 26 are provided around said member within the pan 18 and beneath the lower baffle plate, thus providing air openings above and below each baffle plate. Said baffle plates are supported on lugs 27 and a shoulder 28 formed on member 9, and having openings 29 slightly larger than said lugs to allow convenient removal of said plates. The downwardly bent edge 20 of the cap 17 deflects the fuel downward and particularly when the top plate 13 is highly heated, and the mixture of fuel and air becomes readily vaporized at the outer and lower edge of the annular space 19. These baffle plates also assist in deflecting the descending, burning fuel outward toward the furnace wall.

It has been found in practice that most of the fuel is consumed around the upper part of the burner and above plate 22, which fuel intermingles with the air passing at a high velocity through the restricted air openings 25; but when the fuel is freely supplied in a large quantity, it will descend to plate 23 before being fully consumed. The openings 25 above the plates supply

a proper amount of air for proper combustion, and if a surplus of fuel should descend over the edge of the lower plate 23, then the openings 26 below said plate 23 will supply sufficient air to insure a proper and full consumption of the fuel to prevent it from reaching the pan 10. It is also to be noted that the air passing out through the air openings moves upwardly and in the proper and natural way enters beneath the liquid fuel descending from the plates, thus passing outwardly and upwardly through the fuel and thoroughly mixing therewith. The combined air openings on member 9 furthermore provide less cross section than the cross section of the air conduit 12, and thus cause the air flowing through said conduit to pass at a higher velocity in its passage through these restricted air openings to mingle with the descending fuel, and thereby said air greatly aids in fully atomizing the fuel and producing a complete fuel mixture descending in the form of a thin, annular film or sheet, producing complete combustion and a maximum of heat from the fuel.

While I have illustrated and described the preferred form of construction for carrying my invention into effect this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent, is:

- 40 1. A fluid fuel burner comprising an air distributing member, means mounted at the upper part of said member for distributing said fuel in a thin sheet, baffle plates removably mounted on said member above each other, and a plurality of restricted air openings provided around said member for entering air at increased velocity beneath said descending sheet of fuel to admix therewith and vaporize the same.
- 45 2. A fluid fuel burner comprising a hollow member, a distributing plate removably mounted on and extending radially beyond the upper end of said member, a fuel conduit leading through said member and plate, a cap mounted over said plate to distribute said fuel downward in a sheet, annular plate shaped members with peripheral flanges mounted around said hollow member and arranged to receive said descending fuel successively, and a series of restricted air openings adjacent each annular member to admit air upward and outward beneath said descending sheet of fuel.
- 50 3. A fluid fuel burner comprising a hollow cylindrical member, a distributing plate with

a dished portion at the upper part of said member, a fluid conduit leading through said plate to said dished portion, a cap mounted over said plate and curved downward over the edge thereof, annular flanges mounted around said member arranged to receive said fuel successively, a plurality of series of air openings around said member adjacent each flange, a catch pan beneath said flanges, and air openings between said pan and the lowermost flange.

4. A liquid fuel burner comprising an air distributing member, a seat thereon for receiving an air conduit, a plate with a dished portion and a beveled edge mounted on said member and extending radially therebeyond, a fuel supply pipe leading through said conduit and plate to the dished portion, a cap mounted closely over said plate forming therewith an annular exit space for said fuel and directing said fuel downward, baffle plates mounted on said member over each other and being of increased diameter downward, and air openings around said member between said plates.

5. A liquid fuel burner comprising an air distributing member, a fuel receiving top plate removably mounted on the upper part of said member and carrying a removable cap providing with said top plate an annular space for distributing said fuel in a thin sheet, a plurality of baffle plates mounted on said member above each other, means including lugs on said member and openings on said plates for removably mounting said plates on said member, and a plurality of series of air openings below said top plate and each of said baffle plates.

6. A liquid fuel burner comprising a cylindrical air distributing member, a catch pan formed integral with the lower part of said member, a seat for receiving an air conduit formed on said member at the lower part of said catch pan, a plurality of baffle plates with upturned peripheral flanges mounted on said member and increasing in diameter downwardly, a plurality of air openings in said catch pan and adjacent each baffle plate, and means mounted at the top of said burner for distributing a sheet of fuel downward.

7. A liquid fuel burner comprising a cylindrical air distributing member arranged to be mounted on a furnace grate, a catch pan formed integral around the lower part of said member, an air pipe mounted within said member and being adapted to extend to an air opening on said furnace, openings around said member within said pan, a top plate removably mounted on and extending outwardly from the upper end of said member, a cap removably mounted over said top plate and curved downward over the edge thereof, a fuel supply pipe leading to the space between said top plate and cap, a se-

ries of baffle plates removably mounted between said top plates and pan and arranged for successively receiving the fuel from said top plate, and a plurality of series of air openings provided around said member adjacent each plate.

In testimony whereof I have signed my

name to this specification in the presence of two subscribing witnesses.

ROSCOE V. JEFFERSON.
